UNITED STATES PATENT OFFICE

PAUL ARTHUR, OF ELKHORN, WISCONSIN, ASSIGNOR TO FRANK HOLTON & CO., OF ELKHORN, WISCONSIN, A CORPORATION OF ILLINOIS

SAXOPHONE MOUTHPIECE

Original application filed May 17, 1922, Serial No. 561,570. Divided and this application filed April 2, 1923. Serial No. 629,237.

This application is a division of my application, Serial No. 561,570, filed May 17, 1922, for saxophone mouthpieces and method of making same. The claims in said application are limited to the method of making a saxophone mouthpiece.

My invention relates to mouthpieces for musical wind instruments and is particularly adaptable for saxophones, and the like.

One of the objects of this improvement is the provision of a mouthpiece which can be produced accurately at low cost.

A further object is the provision of a mouthpiece having an inner portion formed in two pieces and joined together so as to provide a smooth interior passage through said pieces, and a binding covering said inner pieces.

A still further object is the provision of a mouthpiece for saxophones, and the like, having a metallic lining made up of parts which may be die castings, or, one part may be formed as a die casting and the other part as an automatic turning machine product.

Another object is the provision of a device of the character mentioned having a metallic lining and a phenolic condensate covering such as that commercially manufactured under the trade name "bakelite" on said lining.

Other objects will appear hereinafter.

An embodiment of my invention is illustrated in the accompanying drawing, forming a part of this specification, and in which—

Fig. 1 is a side view of a mouthpiece embodying my invention;

Fig. 2 is a longitudinal section through the device of Fig. 1;

Fig. 3 is a top view of the device of Fig. 1;

Fig. 4 is a transverse section taken on line 4—4 of Fig. 2; and

Fig. 5 is a view similar to Fig. 3 with the reed and ligature removed.

In the construction of mouthpieces for saxophones and other similar wind instru-

ments now generally in use, a metal inner portion is cut out by hand to afford the required shape of the wind passage therethrough. An opening is first made through the metal body and then this opening worked by hand tools into the proper shape which requires considerable time and makes the mouthpiece quite expensive. With my improvement I provide means for forming such mouthpieces at small cost and in a manner to insure accuracy and uniformity of the product.

I form the central metallic part of the mouthpiece in two pieces. Upon reference to Fig. 2 it will be apparent that the opening 5 through the mouthpiece is circular in cross-section from the end 6 to a portion adjacent a line 7 near the central part of the mouthpiece. This being so I find a metallic part 8 can be formed on an automatic screw or turning machine, not shown, but in general use in machine shops. This part 8 may also be a die casting. The opening 5 is gradually tapering from the end 6 to a point adjacent line 7 and then flaring in somewhat partially spherical form.

The wind passage of the other part 9 of the lining is not cylindrical in cross-section, except for a short distance adjacent line 7, and in view of this part 9 could not easily be made on an automatic screw or turning machine and is therefore preferably made by die casting. Any desirable metals may be used for these linings. I find that a nickel base white metal provides a suitable material for making the part 8 when turned. A suitable material for making the die castings is a tin base metal because this will take a good nickel or silver polish which will remain clean because of the absence of oxidation, although any other desirable die casting metal may be used.

The parts 8 and 9 are preferably arranged so as to have a threaded connection 10 between them for holding such parts in rigid

condition with respect to each other. The joint 7 is arranged so that the adjacent shoulders of parts 8 and 9 fit tightly together so that when the parts have been put together 5 and polished the surface is quite smooth across line 7. This makes a construction which operates equally as well as a solid piece construction. In a conventional construction the curved parts at both sides of line 7 must be cut out with hand tools and great care must be used to insure cutting these parts so as to get the required tones in the instrument. Where part 8 is formed on an automatic turning machine the parts will 10 be duplicates of each other, and where the parts 8 and 9 are die cast they will also be duplicates and no hand finishing will be necessary to afford a proper wind passage through these parts when fitted together in 15 the mouthpiece.

The part 8 is provided with a groove 11 and there is a small groove 12 between the outer parts of the parts 8 and 9 adjacent the threads 20. After the parts 8 and 9 have been screwed 25 together so as to bring their shoulders at line 7 tight, a phenolic condensate, rubber, celluloid, or other material is moulded around said parts 8 and 9 with portions of said moulded parts entering into the annular grooves 10 30 and 11 so that the mouthpiece consisting of the parts 8 and 9 and moulded covering 13 is in effect one solid integral mass. The parts 10 and 11 help to hold the covering 13 tightly in position on the parts 8 and 9.

35 In the drawing, I have indicated a band or ligature 14 having thumb screws 15 for clamping the latter around the mouthpiece. This ligature 14 holds the reed 16 in proper position over the opening of the mouthpiece.

40 It will be apparent that the sizes and cross-sections of the wind passage 5 extending through the mouthpiece may be varied to suit different instruments. An essential part of my improvement is the production of the metallic lining of the mouthpiece in such a manner that it can be produced at low cost and so 45 that accuracy and uniformity of the product will always be had.

Bakelite, a substance now in general use 50 provides a very efficient material for the covering material 13. It is easily moulded in proper position over the metallic lining and has very distinct advantages over hard rubber and many other substances used heretofore for similar covering material. Bakelite will not leave a taste in the player's mouth in use. It will not warp with the 55 changes of temperature and is very durable. It further possesses the advantages of not 60 being easily broken, chipped or cracked.

Bakelite is described under its trade name "bakelite" in the Journal of Industrial and Engineering Chemistry, volume 8, No. 1, of 65 May, 1916, and in C. T. Kniggett's Chemical Encyclopedia, 3rd edition, page 47. The

process of manufacture is described in detail in U. S. Patent No. 942,809.

It will be apparent from Figs. 4 and 5 that the metal lining part 9 has a plane side at opening 17 upon which the reed 16 is held by the ligature. The covering 13 has a plane portion also adjacent the plane portion of member 9, as clearly indicated in Fig. 5, upon which the rear end of the reed 16 engages, as clearly indicated in Figs. 2 and 5. The line 18 indicates approximately where the plane part of the metal part 9 engages the plane part of covering 13, as just mentioned. In the form shown, the reed is of substantially the same width as the plane surfaces just mentioned, but it will be understood that the relative widths of the reed and these surfaces may be varied as desired. An important feature is that the plane surface cooperates with the ligature 14 to hold the reed in proper position over opening 17 so that the desired musical tones can be produced.

I claim:—

1. A saxophone mouthpiece comprising two hollow inner portions rigidly connected together with a smooth wind passage therethrough, there being irregularities in the outer surfaces of said hollow inner portions, and a covering enclosing said hollow inner portions with parts of said covering extending into the irregularities of said surfaces.

2. A saxophone, and the like, mouthpiece comprising two hollow members with a wind passage therethrough and parts of the hollow members adjacent the wind passage fitting tightly together, there being portions at the outer sides of said hollow members spaced apart, and a moulded covering disposed around said hollow members with portions thereof extending in and fitting said space between the hollow members.

3. A saxophone mouthpiece comprising a hollow metallic portion having a bore therethrough with all cross-sections circular; and a separately formed metallic portion threaded to the first-mentioned metallic portion and having a passage therein communicating with the passage in the first-mentioned metallic portion with part of the passage in the second-mentioned metallic portion non-round in a transverse cross-section.

4. A saxophone mouthpiece having an inner lining comprising a hollow metallic portion having a bore therethrough with all cross-sections circular; a metallic portion threaded to the first-mentioned metallic portion and having a passage therein communicating with the passage in the first-mentioned metallic portion with part of the passage in the second-mentioned metallic portion non-round in a transverse cross-section; and a member enclosing said metallic portions.

5. A saxophone mouthpiece embodying in its structure a metallic lining comprising an automatic turning machine product; and a

die cast product rigidly attached to the automatic turning machine product, said turning machine product and die cast product having openings adapted to be aligned when united.

5 6. A saxophone mouthpiece embodying in its structure a metallic lining comprising an automatic turning machine product; a die cast product rigidly attached to the automatic turning machine product; and a moulded covering around said lining securing the aforesaid mentioned parts together, said turning machine product and die cast product having openings adapted to be aligned when united.

10 7. A saxophone mouthpiece comprising an inner metal member having an opening therethrough, said opening being circular at all cross-sections, tapered from both ends to a point intermediate said ends; a second metal member having an opening therein with an irregular cross-section throughout the greater part of its length and said opening registering with the opening in the first-mentioned member; and a threaded connection between said members.

15 8. A saxophone mouthpiece comprising two members one having a portion telescoped into the portion of the other member; a threaded connection between said telescoped portions securing said members together, there being a peripheral groove in one of the members at the adjacent end of the other member; and a moulded covering enclosing said members and disposed in said peripheral groove.

20 9. A saxophone mouthpiece embodying in its structure a metallic lining comprising two separately formed metallic parts attached together; and a covering of moulded material enclosing said parts.

25 10. A saxophone mouthpiece embodying in its structure a metallic lining comprising two separately formed metallic parts connected together and having a wind passage extending through both of said metallic parts, and a covering of a moulded phenolic compound enclosing said metallic parts and rigidly securing them together.

30 11. A mouthpiece for wind instruments comprising a hollow metal shell and a covering for the exterior of said shell made of a phenolic condensate.

35 12. A mouthpiece for a musical wind instrument comprising a hollow metallic shell and a covering for the exterior of said shell comprising a phenolic condensate permanently moulded upon the outer surface of said metallic shell.

40 13. A mouthpiece for a musical wind instrument comprising a hollow metallic shell, the opening within said shell having an enlarged portion between the ends thereof and a covering for the exterior of said shell made

of phenolic condensate moulded upon the outer surface of said shell.

45 14. A mouthpiece for a musical wind instrument comprising a metallic shell having a wind passage therethrough, provided with an opening at one end of said shell for connection with the instrument and a lateral opening adjacent the outer end of said shell for registration with a reed, said wind passage having an enlarged portion between said 70 openings and a phenolic condensate covering on the outer surface of said shell.

50 15. A mouthpiece for a musical wind instrument comprising a metallic shell having a wind passage therethrough provided with a 80 tubular portion at one end for engaging a wind instrument and a lateral opening adjacent the opposite end for registration with a reed, said wind passage being provided with an enlargement between the ends thereof, the wall of said enlargement having a gradual taper joining the wall of said tubular portion to avoid abrupt projections within said wind passage, and a covering of non-metallic material on the outer face of said 85 metallic shell.

55 16. A mouth piece for a musical wind instrument comprising a metallic shell having a wind passage therethrough provided with a tubular portion at one end thereof and a 95 lateral opening adjacent the opposite end thereof, said wind passage being enlarged between said tubular portion and said lateral opening, the walls of the enlarged portion of said passage being gradually tapered to 100 avoid prominent projections and a covering of phenolic condensate permanently moulded on the outer surface of said metallic shell.

60 17. A mouthpiece for wind instruments comprising a hollow core member of metal, 105 and an outer covering of non-metallic material fitted about said core member and adhered to the surface thereof, said core member having flanges thereon overlying the edges of said covering.

65 18. A mouthpiece for a wind instrument comprising a hollow core member of cast metal provided with a thickened portion forming a reed seat, and a phenolic condensate covering for said core member fitted 110 upon, conforming and adhering to the outer surface thereof and having the edges abutting against the side edges of said reed seat.

70 19. A mouthpiece for wind instruments comprising a tubular lining of metal, said lining being bulged outwardly between the ends thereof, and a covering of non-metallic material formed about said lining and completely encircling a portion thereof.

75 20. A tubular metal lining for a wind instrument mouthpiece shaped to form a cavity within the lining having an enlarged portion between the ends thereof, said lining having a laterally directed opening at one end 120 130

and an axially directed opening at the opposite end.

21. A tubular metal lining for a wind instrument mouthpiece having a cavity therein provided with an enlarged portion and a laterally directed opening at one side of said enlarged portion and an axially directed opening at the opposite side of said enlarged opening.

10 In testimony whereof I have signed my name to this specification on March, 23d, A. D. 1923.

PAUL ARTHUR.
